ATTORNEYS

UNITED STATES PATENT OFFICE.

ALVAH J. HOPKINS, OF NEWARK, NEW JERSEY.

BURIAL VAULT.

Application filed April 1, 1922. Serial No. 548,588.

To all whom it may concern:

Be it known that I, ALVAH J. HOPKINS, a citizen of the United States, and resident of Newark, in the county of Essex and State 5 of New Jersey, have invented certain new and useful Improvements in Burial Vaults, of which the following is a specification.

My invention relates generally to burial vaults, more particularly to a base or support for caskets disposed in burial vaults, and consists in the combinations, constructions and arrangements herein described and claimed.

An object of my invention is to provide 15 a base or support which is adapted to be positioned in burial vaults to support a casket therein above the bottom or floor of the vault and to drain any moisture that may collect in the vault from underneath the 20 casket to appreciable distances laterally of the casket, whereby the casket is protected from any detrimental effect of moisture within the vault.

A further object of my invention is to 25 provide a device which is adapted to be positioned within a burial vault to support a casket therein and which has no sharp edges in contact with the casket, such as might occasion cuts or bruises in the casket 30 when the latter is superimposed upon the base or support or on account of the weight of the casket.

A still further object of my invention is 35 to provide a device of the character described which is made of a non-oxidizable material and is adapted to support a casket indefinitely without any deterioration therein and without being affected by corrosion, decay or the attacks of insects or vermin.

40 Other objects and advantages will be apparent from the following description, and the novel features of the invention will be particularly outlined in the appended claims.

My invention is illustrated in the accompanying drawings, forming a part of this application, in which

Figure 1 is a vertical section through a portion of a burial vault, showing a base or support embodying my invention, the view 50 of the support or base being substantially along the line 1—1 of Figure 2.

Figure 2 is a plan view of the base or support,

Figure 3 is a section along the line 3—3 55 of Figure 2, and

Figure 4 is a section along the line 4—4 of Figure 2.

In Figure 1 I show a portion of a burial vault or compartment having vertical walls 1 extending from the floor or bottom wall 2 which may be formed in the earth or may consist of a suitable foundation surface adapted to permit moisture to pass freely therethrough. A support indicated generally at 3 is disposed within the vault or compartment upon the floor or bottom wall 2 and is of less area than the floor or bottom wall, the edges of the support or base being spaced from the walls 1 to provide a space 4 through which moisture may drain from the upper 70 surface of the support or base through the bottom wall 2, as will hereinafter appear.

In the embodiment of the invention illustrated, the support or base 3 comprises a substantially flat body of rectangular configuration. The body 5 may be molded, shaped or formed in any suitable known manner of any suitable material which is non-oxidizable and not subject to injury on account of the attacks of insects, vermin or the like. 75 For example, I may form the body 5 of cement, concrete or any other plastic material which will set hard, or of wood, suitably treated as with creosote or the like to render the same durable and to preclude the attacks of insects or vermin. The bottom face 6 of the body 5 is fashioned to lie close against the bottom wall 2 at all points and is by preference formed with the entire lower or under surface thereof located in the 80 same plane. It will be understood that the contour of the body 5 will be such as to conform to the contour of the interior of the vault or compartment.

The body 5 is formed to provide in the 95 upper face thereof a series of depressions or grooves 7 which extend transversely of the body from one side edge to the other, the series of depressions or grooves extending an appreciable distance from one end of the body to a like distance from the other end of the body and each pair of adjacent depressions or grooves being spaced apart by a relatively raised portion 8. The relatively raised portions 8 extend transversely of the 100 body 5 from one side edge thereof to the other side edge and thus constitute ridges which alternate with the depressions or valleys 7. The ridges 8 and the valleys 7 are 105 arcuate in cross sectional contour, being 110

struck to the radius of a circle so that the apices of the ridges and the portions along the longitudinal median line of the valleys do not provide sharp edges but are symmetrically curved. The width of each ridge 8 is greatest along the longitudinal median line of the body 5 and decreases toward the side edges of the body 5. In consequence, the width of each valley 7 will be less along the longitudinal median line of the body and will increase uniformly toward the side edges of the body.

The said valleys 7 decrease regularly in depth from the side edges of the body 5 to the longitudinal median line of the body 5, being therefore inclined from their ends toward the longitudinal median line of the body 5. The valleys 7 are relatively wide at their ends or in other words at the side edges of the body 5 and converge regularly from the side edges of the body toward the longitudinal median line of the body. The end valleys 7 are deepened intermediate of their ends as indicated at 7' for a purpose which 25 will hereinafter appear.

Relatively short alternating ridges 9 and valleys 10 extend from the end or remote valleys 7 to the end and portions of the side edges of the body 5 as best seen in Figure 2. The ridges 9 and valleys 10 are of arcuate cross sectional contour and are wider at their outer ends than elsewhere, converging together at their relatively narrow inner ends, the point at which their inner ends 35 would meet if sufficiently extended lying in the longitudinal median line of the body 5. The depth of the relatively short valleys 10 is greatest at the outer ends thereof and decreases regularly toward the inner ends 40 thereof. The crests of the ridges 8 and 9 are tangent to a plane parallel to the plane of the under face of the body.

From the foregoing description of the various parts of the device, the operation 45 thereof may be readily understood. It is intended that the series of valleys 7 will be of such length that the end valleys having the relatively deep middle portions 7' will be located adjacent to and in parallelism with the 50 opposite ends of a casket 11 which will rest upon the base 3. The ropes or suspension members passed around the casket 11 when the latter is lowered into position to rest upon the upper face of the body 5 as shown 55 in Figure 1 will rest in the relatively deep portions 7' of the end valleys 7 so that all underlying portions of the ridges 8 will contact at their apices with the bottom of the casket 11 and aid in supporting the latter. 60 Since the apices of the ridges 8 and of the ridges 9 are rounded when considered in cross section it will be apparent that the casket will not be cut or marred when lowered to rest upon the base or by reason of the 65 weight of the casket. Since the portion of

the base or support 3 underlying the casket 11 is formed with ridges on its upper face inclined in all directions from the longitudinal median line of that portion and since the portions of the support or base 3 extending laterally of the casket 11 slope from the casket toward the edges of the base or support 3, any moisture collecting within the vault or compartment will be drained from the portion of the base located beneath the 75 casket to pass over the edges of the base to the underlying wall or bottom 2 and will be absorbed by or percolate through the latter. Since the valleys 7 and 10 are arcuate in cross sectional contour, no obstruction is 80 offered to the flow of moisture to the outer edges of the body.

Obviously, my invention is susceptible of embodiment in forms other than that in which illustrated in the accompanying drawings, and I therefore consider as my own all modifications and adaptations of the form herein disclosed which fairly fall within the scope of the appended claims.

Having thus described the invention, 90 what I claim is:—

1. A base for caskets comprising a substantially flat body portion having alternating grooves and ridges in the upper face thereof, the depth of each groove being greater at its outer end than other points therealong and all of said ridges being tangent at all points along their length to a common plane.

2. A base for supporting caskets comprising a substantially flat body having alternating ridges and valleys in the upper face thereof, said valleys being deepest and widest at their outer ends.

3. A base for supporting caskets comprising a substantially flat body having alternating ridges and valleys in the upper face thereof, said valleys being deepest and widest at their outer ends, and said valleys and said ridges being substantially arcuate in cross sectional contour, the crests of all ridges being tangent at all points along their length to a common plane.

4. A base for caskets comprising a substantially flat body having in the upper face thereof series of alternating ridges and depressions extending transversely of the body, there being valleys at the opposite end of the series, each of said ridges and said valleys being arcuate in cross sectional contour at all points along the length thereof and said valleys being of greatest width and greatest depth at the ends thereof, decreasing in width and depth toward the longitudinal median line of the body, said end valleys having the intermediate portions thereof of greater depth than the corresponding portions of the remaining valleys, as and for the purposes described.

5. A base for caskets comprising a sub-

stantially flat body having in the upper face thereof series of alternating ridges and depressions extending transversely of the body, there being valleys at the opposite ends of the series, each of said ridges and 5 said valleys being arcuate in cross sectional contour at all points along the length thereof and said valleys being of greatest width and greatest depth at the ends thereof, decreasing in width and depth toward the 10 longitudinal median line of the body, said end valleys being located at appreciable distances from the ends of the body and the portions of the upper face 15 of the body extending between the respective end valleys and the corresponding ends of the body being formed with alternating ridges and valleys radiating from the intermediate portions of said end valleys, and being of greatest width at their 20 outer ends and arcuate in cross sectional contour at all points along their length, said radial valleys being of greatest depth at their outer ends. 25 6. A base for caskets comprising a substantially flat body having in the upper

face thereof series of alternating ridges and depressions extending transversely of the body, there being valleys at the opposite ends of the series, each of said ridges and 30 said valleys being arcuate in cross sectional contour at all points along the length thereof and said valleys being of greatest width and greatest depth at the ends thereof, decreasing in width and depth toward the 35 longitudinal median line of the body, said end valleys being located at appreciable distances from the ends of the body and the portions of the upper face of the body extending between the respective end valleys 40 and the corresponding ends of the body being formed with alternating ridges and valleys, radiating from the intermediate portions of said end valleys and being of greatest 45 width at their outer ends and arcuate in cross sectional contour at all points along their length, said radial valleys being of greatest depth at their outer ends, the crests of all of said first named ridges and said second named ridges lying in the same 50 plane.

ALVAH J. HOPKINS.
